PUMPING MECHANISM

John K. Haddaway, Los Angeles, Calif.

Application September 25, 1937, Serial No. 165,711

6 Claims. (Cl. 230—55)

This invention relates generally to fluid displacement mechanisms, and more particularly to pumps of the type which are driven by mechanical vibrations produced electromagnetically.

5 An object of the invention is to provide an electromagnetically driven pump which is structurally characterized by extremely simple driving mechanism, including electromagnetic means and a resonant armature therefor, operatively connected to the pump, and having its period of vibration so correlated with the cycle of alternating current providing the electro-motive force, as to cause maximum vibration of the armature when the pump is subjected to a predetermined 10 load, whereby to operate the pump at maximum efficiency.

Another object of the invention is to provide an electromagnetically driven pump of the above described character wherein the resonant armature for the electromagnet can be of a single or 20 double type, with respect to which the electromagnet is so disposed as to obtain maximum power therefrom which is transmitted directly by the armature to the pump in a manner for the latter to be operated at maximum efficiency, all 25 when alternating current at a predetermined cycle, for which the armature is tuned, is supplied to the electromagnet.

A further object of the invention is to provide 30 an electromagnetically driven pump operating with alternating current vibrating a tuned, resonant armature to obtain exceedingly reliable and quiet operation without radio interference, and to insure long life and maximum efficiency indefinitely by the elimination of all such parts as 35 would require servicing and attention.

A still further object of the invention is to provide an electromagnetically driven pump with 40 which a sound filter or trap is associated by the provision of an enclosed, flexible discharge conduit from the pump, to which the armature vibration and noise of the pumping impulses are confined, so as to effectively prevent transmission of vibrations beyond the discharge conduit, and to 45 muffle all operating noises, as is particularly desirable in the pumping of air into the water of aquariums for aeration.

With these and other objects in view, the invention 50 consists in the combinations, arrangements and functional relationships of elements as set forth in the following specification, and particularly pointed out in the appended claims.

In the accompanying drawings, 55 Figure 1 is a vertical longitudinal sectional

view of one form of pumping mechanism embodying this invention;

Figure 2 is a top plan sectional view taken on the line 2—2 of Figure 1;

Figure 3 is a bottom plan view, with a base 5 section of the enclosing housing removed, and with a portion of the body section broken away to show otherwise concealed parts;

Figure 4 is a vertical longitudinal sectional view of a modified form of pumping mechanism 10 embodying this invention;

Figure 5 is a top plan sectional view taken on the line 5—5 of Figure 4; and showing portions of the mechanism beyond the plane of the section, broken away;

Figure 6 is a bottom plan view of the modified 15 form of pumping mechanism, with a base section of the enclosing housing removed, and with a portion of the body section broken away to show otherwise concealed parts.

Referring specifically to the drawings, and particularly to Figures 1 to 3, inclusive, this form of the invention comprises a rectangular housing 10 of wood or other suitable material, having a base section 11 to which an inverted cup shaped 20 body section 12 is secured by screws 13. The pumping and electromagnetic driving means therefor form a unitary structure supported in the body section 12, and comprise a rigid metal base plate 14, the ends of which are embedded 25 in sponge rubber pads 16—16 forced snugly into the body section 12 so as to provide a cushioning mounting for the aforesaid structure. Fixed to the base plate 14 is the U-shaped core 17 of an electromagnet 18 the winding 19 of which is 30 wound upon one branch of the core for electromagnetic co-action therewith. Alternating current as generally supplied to domestic consumers, is adapted to be supplied to the winding 19 by conductors 20—20 which pass through a suitable 35 opening in the body section.

A bar armature 21, of flexible, flat strip magnetic metal, has one end thereof angularly bent and secured by rivets 22 to the other branch of the core 17 so as to be supported thereby in 40 magnetizable relationship to the core for vibration in response to the supply of alternating current to the winding 19. The period of vibration of the resonant armature thus provided can be varied by weights 23 slidably mounted on the 45 armature for movement along the length thereof, and securable in any adjusted position by set screws 24.

Between the electromagnet 18 and the free end 50 of the armature 21 the latter is operatively con- 55

nected directly to a pump 25 comprising a circular cup-shaped casing 26 fixed to the base plate 14 and co-acting with a ring 27 and screws 28 to secure a resilient rubber diaphragm 29 to the casing 5 to form a flexible wall thereof. At opposite sides of the diaphragm 29 are metal disks 30-30 through which passes a rigid operating rod 31 secured to the disks by nuts 32-32 threaded on the rod at the opposite sides of the disks, whereby 10 to also clamp the diaphragm between the disks. The other end of the rod 31 is secured in any suitable manner at 33 to the armature 21 adjacent the free end thereof, so that when the armature is vibrated, its vibratory movement will be transmitted to the rod 31 and thus correspondingly 15 vibrate the diaphragm.

The casing 26 is provided with an intake port 34 and a discharge port 35, respectively, controlled by spring loaded check valves 36 and 37 20 so that when the diaphragm is vibrated, air will be drawn through the port 34 into the chamber 38 defined by the casing and diaphragm, and will be forced from the chamber through the port 35, whereby to effect a pumping action.

25 Communicating with the port 35 is a flexible discharge conduit 39 in the form of a length of resilient rubber hose which is coiled freely in the housing 10 and passes through an opening in one of the pads 16 for connection to one end of a 30 metal tube 40 supported in an end wall of the body section 12. To the other end of the tube 40, a suitable conduit 41 is connected and is adapted to conduct the air from the pump to a point of use.

35 At its outlet end, the discharge conduit 39 is provided with a plug 42 of felt or other suitable porous material which coacts with the conduit to confine thereto the pumping impulses, and to absorb the vibration of the pump. It will be appreciated 40 that the conduit 39 will slightly expand and contract at each pumping impulse, due to the resistance offered by the plug 42 to the free passage of air which will thus be discharged into the conduit 41 in a continuous stream. As the 45 conduit 39 is enclosed within the housing 10, the noise of the pumping impulses in the tube will be effectively muffled.

In the operation of the invention, the period 50 of vibration of the resonant armature 21 is varied by suitable adjustment of the weights 23, until the number of vibrations in a unit of time conforms to the number of reversals in the cycle of alternating current employed, this adjustment being effected when the pump is placed under a 55 predetermined working load, so as to obtain maximum operating efficiency from the pump. In using sixty cycle current, the number of vibrations per second to which the armature is tuned, will be one hundred twenty per second, 60 which tuning will be attained by checking against the operating efficiency of the pump under a predetermined working load.

65 Reference will now be had to Figures 4 to 6, inclusive, in which is shown a second form of the invention embodying a double type resonant armature instead of the single type previously described.

This form of the invention comprises a rectangular housing 10a of wood or other suitable 70 material, composed of a base section 11a to which an inverted cup-shaped body section 12a is secured by screws 13a. As in the previously described form of the invention, the pumping and electromagnetic driving means therefor form a 75 unitary structure supported in the body section

12a, and comprise a rigid L-shaped metal base plate 14a, the ends of which are embedded in sponge rubber pads 16a-16a forced snugly into the body section 12a so as to provide a vibration absorbing mounting for the structure. Fixed by a 5 screw 43 to the base plate, at one end thereof, is a resonant armature 44 of magnetic metal which has the generally U-shaped contour of a tuning fork so as to provide parallel arms 45-45 and a portion 46 connecting the arms at one end thereof. As the connecting portion is directly secured by the screws 43, to the base plate, the arms 45 are supported to freely vibrate.

Fixed to the base plate between the arms 45, and adjacent the connecting portion 46, is an 15 electromagnet 47, the ends of whose core 48 are disposed in magnetizing relation to the arms. Alternating current as generally supplied to domestic consumers is adapted to be supplied to the winding 49 of the electromagnet 47 by conductors 50-50 (Figure 6) which pass through a suitable opening in the body section 12a of the housing. The period of vibration of the arms 45 can be varied by weights 51-51 slidably mounted on the arms for adjustment along the 20 lengths thereof, and securable in any adjusted position by set screws 52-52.

Disposed between the arms 45 and between the electromagnet 47 and the free ends of the arms, is a pump 53 including a valve body 54 fixed to the base plate 14a and defining a chamber 55 having an intake port 56 and a discharge port 57 at opposite ends. A filtering and silencing plug 58 of felt or other suitable material spans the intake port 56, and spring loaded check valves 30 59 and 60, respectively, control the ports, as clearly shown in Figure 4.

Between the ports 56 and 57, the chamber is provided with a port 61 defined by a metal tube 62 having a sealed connection with the breather 40 chamber 63 of a flexible bellows 64 of circular form. This bellows can be constructed of resilient rubber, and has its flexible side walls 65-65 connected rigidly to the arms 45-45 by threaded rods 66-66 secured to the arms by pairs of nuts 45 67-67, and to the respective walls 65-65 by nuts 68-68 and pairs of metal disks 69-69 between which the walls 65 are clamped.

The rods 66 are co-axially related to each other and are connected to the walls 65 axially thereof 50 so as to co-act with the bellows in effecting a pumping action in the breather chamber 63 in response to vibration of the arms 45.

Communicating with the port 57 is a flexible discharge conduit 70 in the form of a length of 55 flexible rubber hose which is coiled freely in the housing 10a and passes through an opening in one of the pads 16a for connection to one end of a metal tube 71 supported in an end wall of the body section 12a. To the other end of the tube 60 71 a suitable conduit 72 is connected and is adapted to conduct the air from the pump to a point of use.

At its outlet end the conduit 70 is provided with a plug 73 of felt or other suitable material. 65 As the conduit 70 functions in a manner identical to that of the conduit 39 in the first described form of the invention, further detailed description will be dispensed with.

The operation of this form of the invention is 70 as follows:

By adjustment of the weights 51, the period of vibration of the resonant arms 45-45 is made to conform to the number of reversals in the cycle of alternating current supplied to the elec- 75

tromagnet 47, this adjustment being effected when the pump is placed under a predetermined working load so as to obtain maximum operating efficiency from the pump, all in the same manner as with the first described form of the invention.

It will be clear that, as the current flow in the winding 49 approaches a maximum in either direction, equal pulls will be exerted by the core 48 to simultaneously draw the arms 45 towards each other and compress the bellows 64, thus reducing the capacity of the breather chamber 63 and forcing air from the valve chamber 55 through the discharge port 57. As the current flow in the winding recedes to zero, the flexibility of the resonant arms causes them to simultaneously move away from each other and thus expand the bellows 64 to increase the capacity of the breather chamber 63 and suck air into the valve chamber 55 through the in take port 56. This operation is repeated upon each reversal of current in the winding 49 so as to effect a pumping action upon the air, the pumping impulses being absorbed in the coiled conduit 10 so as to deliver a continuous stream of air to the conduit 12 for use as desired.

What is claimed is:

1. In pumping mechanism, an electromagnet; a U-shaped bar armature, between the spaced arms of which the electromagnet is disposed with the ends of its core in magnetizing relationship to said arms; means anchoring said armature at its closed end, with said arms free to be vibrated simultaneously and oppositely in response to the supply of variable current to the winding of the electromagnet; a pump disposed between said arms, and having a breather chamber provided with oppositely disposed movable walls; and means operatively connecting said movable walls to said arms, to expand and contract the breather chamber in response to vibration of the arms as aforesated.

2. In pumping mechanism, a base; an electromagnet supported by the base; a U-shaped resonant bar armature supported at its closed end by the base, with said electromagnet disposed between the spaced arms of the armature in magnetizing relationship thereto so as to vibrate the arms simultaneously and oppositely in response to the supply of variable current to the electromagnet; a pump disposed between said arms and including a plurality of relatively movable means operable to effect a pumping action when moved; and means operatively connecting the arms of the armature to said movable means of the pump to actuate same in response to vibration of the arms.

3. In pumping mechanism, a base; an electromagnet supported by the base; a U-shaped resonant bar armature supported at its closed end by the base, with said electromagnet disposed between the spaced arms of the armature in magnetizing relationship thereto so as to vibrate the arms simultaneously and oppositely in response to the supply of variable current to the electromagnet; a pump including a valve chamber supported by the base, and a breather chamber in communication with the valve chamber and having movable walls; and means operatively connecting the movable walls of the breather chamber to said arms so as to expand and contract the breather chamber alternately in response to vibration of the arms.

4. In pumping mechanism, a base; an electromagnet supported by the base; a U-shaped resonant bar armature supported at its closed end by the base, with said electromagnet disposed between the spaced arms of the armature in magnetizing relationship thereto so as to vibrate the arms simultaneously and oppositely in response to the supply of variable current to the electromagnet; a pump including a valve chamber supported by the base, and a breather chamber in communication with the valve chamber and having movable walls; and rigid members co-axially arranged and secured to said movable walls and to said arms so as to expand and contract the breather chamber in response to vibration of the arms.

5. In pumping mechanism, an armature having spaced arms; means mounting the armature for vibration of said arms; an electromagnet in magnetizing relationship to said arms to vibrate the latter in response to the supply of variable current to the electromagnet; a pump including a plurality of movable means operable to effect a pumping action when moved; and means operatively connecting said arms to said movable means of the pump to actuate same in response to vibration of the arms.

6. In pumping mechanism, an armature having spaced arms; means mounting the armature for vibration of said arms; an electromagnet in magnetizing relationship to said arms to vibrate the latter in response to the supply of variable current to the electromagnet; a pump including a plurality of relatively flexible walls operable when relatively moved, to effect a pumping action; and means operatively connecting said arms to said walls, respectively, to relatively move same in response to vibration of the arms.

JOHN K. HADDAWAY.
